UNITED STATES PATENT OFFICE.

HENRY A. CHRISTY, OF KENILWORTH, ILLINOIS, ASSIGNOR TO AMERICAN CAR ROOF CO., OF CHICAGO, ILLINOIS, A CORPORATION OF ILLINOIS.

RAIL-JOINT.

1,153,153.

Specification of Letters Patent.

Patented Sept. 7, 1915.

Application filed June 21, 1915. Serial No. 35,194.

To all whom it may concern:

Be it known that I, HENRY A. CHRISTY, a citizen of the United States, residing at Kenilworth, in the county of Cook and State 5 of Illinois, have invented certain new and useful Improvements in Rail-Joints, of which the following is a specification.

My invention pertains to features of novelty and improvement in railroad rail- 10 joints or fastening-devices for securing together the ends of abutting rails, which, as is well understood, are subjected to severe strains and shocks tending to interfere with their proper holding or clamping functions.

15 Devices of this general character, if they are to be effective in operation, must accomplish several results: They must not become loosened either from the rails or the ties under the severe pounding action of the locomotives and cars. They must maintain the 20 ends of adjoining rails in proper alinement, and they should also support and brace the heads of the rails. It is further desirable that they should have the capability of being 25 tightened so as to meet or fulfil at all times these desirable, and, in fact, necessary requirements.

In carrying out these various objects and aims, I have devised a type of rail-clamp or 30 joint which efficiently holds the rails together and embodies a rocking wedge feature capable of tightening adjustment, which, while simple in structure and economical to manufacture, braces the rail-head 35 satisfactorily, produces a balanced effect or strain on the base of the appliance, and does not necessarily depend upon spikes for maintaining its parts in proper operative relation.

40 In order that those skilled in this art may be fully advised of the features of construction and operation which differentiate this new appliance from those of the prior art, I have illustrated a preferred embodiment of 45 the same in the accompanying drawing forming a part of this specification and to which reference should be had in connection with the following detailed description.

50 In this drawing: Figure 1 is a vertical cross-section through one of the rails, the joint structure, and a portion of one of the ties; Fig. 2 is a side elevation of the device applied to the ends of alined rails, and Fig. 55 55 illustrates the base-plate of the appliance in perspective.

The device comprises a base-plate 10 of suitable length having a central longitudinal groove or depression 11 for the reception of the bases of the end portions of the rails 12 and 13, the width of such channel being substantially the same as that of the rail bases, as is clearly illustrated in Fig. 1. This base or foundation plate is secured to the ties by a plurality of spikes 14, received in suitable holes 15, through the plate 10 near its edges. 60 Outwardly of the margins of the depression 11 this supporting-plate 10 has a pair of longitudinal, inwardly-curved flanges or ribs 16 and 17 providing cavities or sockets on their inner faces or sides, as is shown in Fig. 65 1. An angle fish-plate 18 is employed on each side of the rails having a curved lower or outer edge 19 accommodated in the corresponding cavity of the rib 16 or 17, as the case may be. At their upper edges these 70 75 fish-plates bear against the under faces of the rail-heads and are slightly beveled at 20, whereby, as they are drawn inwardly, they will act as rocking wedges firmly holding the rails in place and bracing or supporting 75 80 85 their heads.

Each plate 18 has a rocking bearing on the top faces of the rail bases at a point 21 substantially in a plane normal or at right-angles to the longitudinal central-portion of the under surface of the rail-head, thus bringing the place of such rocking bearing outwardly of the rail-head. As is illustrated, the fish-plates as well as the rail-webs are apertured in alinement or register at 22, 23, for the accommodation of a suitable number of tightening bolts equipped with the usual nuts, which, of course, if desired, may be supplied with lock washers, not shown. 90 By tightening the nuts of such bolts, the fish-plates are caused to rock on their bearings on the rail bases and their upper wedge-portions under the rail-heads can be thus drawn inwardly with great force, resulting in efficiently locking or clamping the rail-ends together, as well as effectively bracing and supporting the rail-heads. Of course, the lower edges of the fish-plates cannot move outwardly by reason of their contact 95 100 with the flanges or ribs 16, 17, and their pressure on the latter is substantially balanced. As shown, the lower edges of the fish-plates and the ribs are so shaped that they are sufficiently loosely received in the rib pockets so that the rocking of the plates 105 110

referred to, is not interfered with. By 5 locating the bearings of the plates at substantially the points indicated, a very slight taper or bevel at the upper edges of the fish-
5 plates becomes especially powerful for the purposes indicated. Ample space is left between the plates and the rail-webs and the outer faces of the former around the bolt-holes may be conveniently rounded or 10 vexed to provide satisfactory bearings for the bolt-heads and nuts, as the case may be.

Although I have herein set forth in detail 15 one desirable embodiment of the invention, it is to be understood that the invention is susceptible of a variety of embodiments and that many minor mechanical changes may be made in the structure presented without departure from the substance of the invention and without the sacrifice of any of its real 20 advantages.

I claim:

1. In a rail-joint construction of the character described, the combination of a base-plate 25 on which the ends of abutting rails are adapted to rest, said base-plate having a longitudinal socket above the bases of such rails, a fish-plate adapted to be disposed longitudinally of the abutting rails out of contact with their webs and with its lower edge 30 accommodated in said base-plate socket, said fish-plate being constructed with a length-wise bearing on its lower-portion adapted to bear on the bases of the rails outside of their heads only, said fish-plate also having a 35 wedge-upper-portion adapted to engage the under surfaces of the rail-heads, and means to adjustably rock said fish-plate transversely of said bearing to tighten said wedge-portion under the rail-heads, substantially as described.

2. In a rail-joint construction of the character described, the combination of a base-plate adapted to support the ends of abutting rails and provided with oppositely disposed 45 longitudinal sockets positioned above the bases of such rails, a pair of fish-plates adapted to be disposed longitudinally of and on opposite sides of the abutting rails and out of contact with their webs, each of said 50 fish-plates having its lower-edge portion

constructed for accommodation in one of said longitudinal sockets, each of said fish-plates constructed with a longitudinal bearing on its lower-portion adapted to bear on the bases of the rails outside of their heads only, each of said fish-plates also having a wedge-upper-portion adapted to engage the under surfaces of the rail-heads, and means common to both of said fish-plates to adjustably rock said fish-plates transversely of the rails on their bearings, to tighten such wedge-portions under the rail-heads, substantially as described.

3. In a rail-joint construction of the character described, the combination of a pair of 65 fish-plates constructed to have rocking bearings on the opposite base portions of abutting railroad rails, each of said fish-plates constructed to be out of contact with the rail webs and having a wedge-portion adapted 70 to engage the under surfaces of the rail-heads, means common to both of said fish-plates to rock them on said rail-base bearings to tighten their wedge-portions under the rail-heads, said fish-plate bearings on 75 the rail-bases being at points substantially in planes normal to the central portions of the rail-head surfaces engaged by the wedges, substantially as described.

4. In a rail-joint construction of the character described, the combination of a base-plate adapted to receive the ends of adjacent rails and provided with longitudinal sockets along its opposite sides, a pair of angle fish-plates each having a lower edge-portion 85 adapted to be loosely received in one of said base-plate sockets, each of said fish-plates being constructed to be out of contact with the rail webs and to have a rocking bearing on the bases of the rails at a point 90 substantially in a plane normal to the longitudinal central portion of the corresponding under surfaces of the rail-heads and having a wedge-portion adapted to engage the under surfaces of the rail-heads, and means to rock said fish-plates on such bearings to tighten their wedge-portions under the rail-heads, substantially as described.

HENRY A. CHRISTY.
